US00D798921S

(12) **United States Design Patent** (10) **Patent No.:** **US D798,921 S**
Frota de Souza Filho (45) **Date of Patent:** **** Oct. 3, 2017**

(54) **CUTTING HEAD FOR MODULAR DRILL**(71) Applicant: **Kennametal Inc.**, Latrobe, PA (US)(72) Inventor: **Ruy Frota de Souza Filho**, Latrobe, PA (US)(73) Assignee: **KENNAMETAL INC.**, Latrobe, PA (US)(**) Term: **15 Years**(21) Appl. No.: **29/541,762**(22) Filed: **Oct. 7, 2015**(51) LOC (10) Cl. **15-09**

(52) U.S. Cl.

USPC ..... **D15/139**; D8/70(58) **Field of Classification Search**

Primary Examiner — Darlington Ly(74) *Attorney, Agent, or Firm* — Ian K. Samways(57) **CLAIM**

The ornamental design for a cutting head for modular drill, as shown and described.

DESCRIPTION

FIG. 1 is a front isometric view from above of the cutting head for modular drill showing my new design;

FIG. 2 is a top isometric view thereof;

FIG. 3 is a right side elevation view thereof;

FIG. 4 is a left side elevation view thereof;

FIG. 5 is a front elevation view thereof;

FIG. 6 is a bottom plan view thereof; and,

FIG. 7 is a top plan view thereof.
